UNITED STATES PATENT OFFICE.

I. RULOFSON AND D. DE GARMO, OF ROCHESTER, NEW YORK.

IMPROVEMENT IN PLOWS.

Specification forming part of Letters Patent No. 31,677, dated March 12, 1861.

To all whom it may concern:

Be it known that we, ISAAC RULOFSON and DANIEL DE GARMO, of Rochester, in the county of Monroe and State of New York, have invented a new and useful Improvement in Plows; and we do hereby declare that the following is a full, clear, and exact description of the same, reference being had to the accompanying drawings, making a part of this specification, in which—

Figure 1 is a side elevation of the implement, with a section of the rests *u* and *v*, through the plane indicated by the red line in Fig. 2, removed. Fig. 2 is a plan or top view with the rear portion of the beam *B* removed.

Similar letters refer to corresponding parts in both figures.

This invention consists in the arrangement of devices hereinafter described.

Any desired pattern may be used for the general construction of the plow, except the landside, the handle-plate *a* of which we extend up to the under side of the beam, as seen in Fig. 1, and connect the top of it with the top of the standard *d* by means of the web or plate *f*, and on the top of this plate is cast the rests *u* and *v* for the beam *B*. These rests

should extend sufficiently each way to admit of a lateral change or movement of the beam to adapt the plow to two or to three horses, (when the three are driven abreast,) and through the said rests are formed the open slots *c*, for the clamping-bolts *b* to pass through. The said rests *u* and *v* are recessed on the under side, as seen in Fig. 1 at *e*, to make room for the head of the bolts *b*, which are prevented from turning when the nuts *n* are turned by the heads, which are square, fitting between the flange on each side of the recess *e*. The upper face of the rests *u* and *v* are slightly serrated, to prevent the beam *B* from moving when the clamping-bolts *b* are tightened.

What we claim as new, and desire to secure by Letters Patent, is—

The arrangement of the beam *B*, plate *f*, rests *u* and *v*, slots *c*, and clamping-bolts *b*, the whole being constructed substantially in the manner herein shown and described.

ISAAC RULOFSON.
DANIEL DE GARMO.
